UNITED STATES PATENT OFFICE

OSCAR LEBECK, OF NEW YORK, N. Y.

DESIGN FOR A CHILDREN'S CHAIR OR SIMILAR ARTICLE

Application filed August 31, 1932. Serial No. 44,723. Term of patent 7 years.

To all whom it may concern:

Be it known that I, OSCAR LEBECK, a citizen of Germany, residing at New York city, in the county and State of New York, have invented a new, original, and ornamental Design for a Children's Chair or Similar Article, of which the following is a specification, reference being had to the accompanying drawing, forming part thereof.

In the drawing, Fig. 1 is a front elevation of the article, showing my new design; and Fig. 2 a side elevation thereof.

I claim:

The ornamental design for a children's chair or similar article, as shown.

OSCAR LEBECK.
